BASE FOR OPTICAL INSTRUMENTS

Dennis H. Merino, Harbor City, and Floyd E. Schlau,
Palos Verdes Peninsula, Calif., assignors to Mattel,
Inc., Hawthorne, Calif., a corporation of Delaware

Filed Sept. 5, 1969, Ser. No. 19,042

Term of patent 14 years

Int. Cl. D16—08; D21—02
U.S. Cl. D57—1

FIG. 1 is a perspective view of the base for optical instruments embodying our new design;

FIG. 2 is a side elevational view thereof;

FIG. 3 is a front elevational view thereof;

FIG. 4 is a top plan view thereof; and

FIG. 5 is a bottom view thereof.

We claim:

The ornamental design for a base for optical instruments, as shown.
